UNITED STATES PATENT OFFICE

KOBY KOHN, OF NEW YORK, N. Y., ASSIGNOR TO CHATHAM SPECIALTY CORPORATION, OF NEW YORK, N. Y., A CORPORATION OF NEW YORK

COVERING FOR TOY TORPEDOES

Application filed June 8, 1929. Serial No. 369,461.

This invention relates to pyrotechnics and more particularly to the provision of a gas-tight and water-proof covering for certain fireworks.

It is a general object of the present invention to provide a novel and improved water-proof and gas-tight covering for pyrotechnic devices and a method of applying the same.

Specifically the invention comprises developing various pyrotechnic devices with a metal covering preferably seamless and homogeneous.

Among the numerous features of novelty of the invention may be specifically mentioned: the use of the process of electro-deposition of metal for providing a continuous gas-tight covering about various pyrotechnic devices; the coating of fireworks such, for instance, as toy torpedoes with a covering of metal over a frangible casing so that the casing can be broken within the metal shell to cause explosion and the gases confined temporarily by the metal to produce a loud report upon disruption of the metal; the provision in the metal coating of one or more "zones of weakness" or sections of less thickness or strength than others to disrupt initially so that the largest part of the debris of the inner frangible casing is held within the ruptured metal shell and thus prevented from flying under the force of the explosion.

The invention also includes unique features involved in the method of applying metal coverings to pyrotechnic devices.

While the invention has been shown and described particularly in connection with toy torpedoes of globular shape, it is to be understood that it is not limited to this particular pyrotechnic but is of wide scope and may be used on blasting cartridges, fire-crackers, and various other pyrotechnic devices where it is particularly desirable either to insure their water-tightness or moisture-proofness, or to provide a tough gas-tight casing to enhance the explosion, and it is intended that the invention be only limited in accordance with the claims appended to the following application.

In the drawings accompanying the application:

Figure 1 is an elevation of a toy torpedo constructed according to the present invention;

Figure 2 is a vertical section through the same;

Figure 3 shows a torpedo in a plating bath arranged to receive less metal coating on one portion of its surface than on the remainder;

Figure 4 shows a further development in the method of providing "zones of weakness";

Figure 5 shows a still further method of providing a "zone of weakness";

Figure 6 is an elevation, partly broken away to show the weakened portion of the casing resulting from the process using the apparatus of Figure 5; and

Figures 7 and 8 show two steps in a method of providing a pair of weakened zones in the coating.

In the manufacture of pyrotechnics there are often occasions where it is necessary to provide a water-proof casing or covering for various articles or where it is desirable to have a gas-tight covering about, for instance, explosive devices to increase the volume of sound by holding the gases until they have accumulated sufficient pressure to rupture the casing. The present invention contemplates forming such a covering of metal and more particularly of electro-deposited metal or metal deposited by spraying or in any other suitable fashion to form a more or less homogeneous, continuous surface. For purposes of convenience only, the invention is disclosed in connection with the form of toy torpedo shown in my Patent No. 1,670,814, for "safety torpedoes", granted May 22, 1928.

As seen in Figure 2 of this application, a torpedo constructed according to that patent is formed from a casing or container 10 of some frangible material such as a molded bitumen or pitch composition having a central compartment 11 closed by a sealed cap 12 formed of the same material. The particular torpedo in question has a central member 13 projecting up into the cavity 11 with its surface and the surface of the cavity walls coated with abrasive material 14 so that when

the casing is broken by impact and more particularly when the projection 13 is broken off from impact, the explosive 15 will be abraded and ignited.

5 In accordance with the patent, it is necessary that there be provided a more or less flexible, gas-tight covering around the explosive container, for, owing to its frangibility, the main container does not provide any 10 confinement for the gases resulting from the burning explosive so that but a slight puff would result if the casing alone were used. The flexible, gas-tight covering yields sufficiently upon impact to permit the inner casing to break and of itself confines the increasing volume of gas until the pressure is sufficient to rupture the covering. This results in a loud report.

In accordance with the present invention, 20 this outer covering 16 is formed of metal, preferably of some electro-deposited metal such as copper, brass, iron or the like. The surface of the inner casing being non-conductive must be suitably prepared in order that 25 the metal covering can be electro-deposited thereon, although it will be obvious that other ways of applying the metal may be resorted to, such, for instance, as dipping, spraying, or otherwise depositing, or by crimping or 30 spinning of sheet metal. However, the main object of the invention is to provide electro-deposited metal, and for this purpose the surface of the casing 10 is suitably coated with a layer 17 of some adhesive substance 35 or some substance which softens the surface of the casing to make it tacky. As an example of the adhesive material may be mentioned shellac, kumar, or other varnishes, and of the second substance, benzol or some other 40 solvent or partial solvent of the material of the casing. This sticky layer is then coated with a layer 18 of an electrical conductor, such, for instance, as bronze powder, copper dust, fine iron filings, graphite, plumbago, or 45 the like, and thereafter the torpedo is immersed in a suitable plating bath and, in accordance with well known principles, becomes the cathode in an electric circuit of which the anode may be a sheet of the metal 50 to be plated.

For experimental purposes or for small production, each torpedo may be suspended from a wire connected to the negative side of the circuit, but obviously this would be unsuitable where large quantity production is necessary, and here resort may be had to the use of a "barrel" or basket in which a large number of the torpedoes are placed and tumbled to receive a coating on all sides, 55 contact being made between the various torpedoes and the metal basket.

It has been found by actual experiment that a torpedo having a pitch mastic explosive container when covered with an electro- 60 plated covering of approximately .005 of an

inch thick will give an exceedingly loud report and without any danger to the user from flying metal, for the covering is ruptured in only one or two places from which the gas issues, thus leaving the detritus largely enclosed within the ruptured casing lying upon the ground substantially at the place of explosion.

The process and article just described are a great improvement over the present practice where the casing of a torpedo is either of paper, wood fiber, sawdust, or the like stuck together with some suitable adhesive. Torpedoes of this type require from 24 to 48 hours' drying in an oven to remove all the moisture, and there is grave danger of the heat used for this drying causing premature explosions. According to the present invention, the covering can be placed on in several hours, and no drying is necessary. 85 The metal covering is particularly ideal for toy torpedoes having a frangible explosive container in that it acts as a protecting structure when the torpedoes are packed or stored in warm places. If the pitch mastic is used to make the casing and a number of torpedoes are packed in a single carton, the weight of those uppermost will be carried to some extent by those on the bottom of the carton, and there is a tendency toward deformation, but 90 the metal covering obviates this difficulty and will carry considerable weight without distortion. It furthermore gives absolute insurance against the entrance of moisture which has been one of the "bug-bears" of 100 fireworks manufacturers resulting in a great number of misfires. The pitch mastic explosive container is of particular value for use with a metal covering, since it is initially water-tight and can be placed in a plating bath without difficulty.

As is well-known, the texture of electro-deposited metal can be of various consistencies in accordance with the rate of deposition, current density, throwing power of the solution, and the use of "additions" in the solution. It is, of course, highly desirable in this present device to have the metal of such texture as to give it considerable tenacity so that any rupturing which takes place tears but a small hole in the covering which permits the débris of the inner container to remain within the covering. In this connection it has been found by experiment that it is sometimes highly desirable to provide one or more of what may be termed "zones of weakness" in the coating to insure rupture at particular places. This will prevent, for instance, such happenings as the whole globe dividing in two parts, each traveling in an opposite direction as the result of the explosion. Figures 3 and 8 suggest various methods of providing a weakened zone in the cover.

In Figure 3 a torpedo 20 is shown in the

plating bath supported on a cathode 21 of conducting material connected to the generator and provided with a projection 22 having its top surface shaped to fit the contour 5 of the torpedo casing and having all the remainder of the cathode covered with insulation as 23. If the plating takes place under these conditions, it is obvious that there will be no covering on that portion of the casing 10 which contacts with the projection 22, or if the fit is not exact, there will be but a thin covering at this place so that rupture of the covering will be insured in the zone covered by the weakest cover.

15 Figure 4 shows a cathode 25 supporting a torpedo 20, and it is assumed that the whole is arranged in a plating bath. Here there are two points or two zones of contact between the inner casing and the cathode 25 20 which is of trough-like form. This will provide a pair of zones of weakness spaced some distance apart, in the construction shown about 90°.

Figure 5 shows a cathode 26 provided with 25 a series of holes 27 therein and covered with insulation everywhere except at the edges of the holes as 28. If torpedoes are placed over each hole and plated, they will receive a coating such as shown in Figure 6 where the main 30 coating 16 is provided with an annular zone 29 of no coating, or at most a very thin coating, thus insuring that the disruption of the casing shall take place at this particular zone.

In the arrangement shown in Figures 7 35 and 8, use is made, for instance, of a device similar to that shown in Figure 3, and Figure 7 discloses the torpedo casing 10 in elevation having received an initial coating 30 on all but the surface resting on the cathode 21. After this coating has attained a thickness of, 40 say, .003 of an inch, the torpedo is moved so that another portion rests on the cathode. In Figure 8 the torpedo is shown as having been rotated through 180° although this is 45 not necessary. A second coating of, say, .005 of an inch is then applied. This is homogeneous with the first coating, and the dividing surface is only shown in Figure 8 by the dotted circle 31. This second coating will be 50 applied to the portion 32 that was not plated initially, and the portion 33 initially plated will not receive the second coating so that there will be a zone at the top having a coating 55 only as thick as the second application and one at the bottom having a coating as thick as the first application of metal, whereas as the rest of the torpedo will have a coating approximately .008 of an inch thick.

The electro-deposition of metal by the process 60 which leaves one or more weakened zones has several advantages. It does not seriously mar the appearance of the finished article, and it permits of a convenient way of providing electrical contact with the torpedo.

55 Lately there have been developed processes

for electro-deposition of nonconducting materials such, for instance, as rubber and the present invention contemplates the use of such processes and materials and is not limited to metal coverings. In the following 70 claims it is intended that the expression "electro-deposited matter" shall cover all material deposited by the use of an electric current.

Having thus described the invention, what is claimed as new and desired to be secured by Letters Patent is:

1. A toy torpedo comprising a casing of frangible material having a cavity, explosive compound in said cavity and a completely enveloping covering of thin metal. 80

2. A toy torpedo comprising a casing of frangible material having a cavity, explosive compound in said cavity and a gas-tight covering for said casing composed of a continuous metal envelope. 85

3. In a toy torpedo, in combination, a tight casing of frangible, moulded material having a cavity therein, explosive and abrasive means in said cavity adapted to cause detonation upon material deformation of said casing, and a gas-tight, metal envelope around said casing. 90

4. In a toy torpedo adapted to be exploded by impact, in combination, a container of frangible material, an explosive enclosed therein and a flexible metal covering enclosing said container. 95

5. A toy torpedo including in combination, a frangible casing, an explosive compound therein, means to explode said compound upon the breaking of said casing and a readily bendable metal covering closely enveloping said casing. 100

6. A firework including a pyrotechnic compound, a surrounding casing of protective material and a tight metal covering completely enveloping said casing, said covering having a zone of thinness to localize 105 the initial disruption. 110

7. A firework including a pyrotechnic compound, a surrounding casing of protective material and a tight metal covering completely enveloping said casing, said covering having a plurality of zones of thinness to localize the initial disruption. 115

8. A firework including a pyrotechnic compound, an enclosing means for said compound and a plated metal casing for said means, said casing having at least a single zone where the metal is materially thinner than in the remainder of the casing. 120

9. A gas-tight covering for a firework composed of an envelope of deposited metal 125 the major portion of which is of substantially uniform thickness and the remainder of less thickness.

10. A toy torpedo comprising a casing of frangible material having a cavity, explo- 130

- sive compound in said cavity, a gas-tight covering for said casing composed of a seam-less metal envelope having a zone of weakness.
- 5 11. A toy torpedo having an outer, gas-tight covering of metal and means to cause initial disruption of said metal within a pre-determined zone upon explosion.
12. A firework comprising an explosive 10 compound, a container for said compound, a gas-tight, deposited-metal coating enclosing said container, means to detonate said compound upon impact, said coating being deposited in such a manner as to provide a 15 zone of initial disruption upon explosion.
13. A toy torpedo including a casing having a closed cavity, explosive material in said cavity and a covering of electro-deposited matter enveloping said casing.
- 20 14. In a toy torpedo, in combination, a completely water-proof casing having a closed internal cavity, explosive material in said cavity and a coating of electro-deposited matter enveloping said casing.
- 25 In testimony whereof I hereunto affix my signature.
